DRAIN COCK WRENCH

Edward J. Brouhard, Des Moines, Iowa

Application November 3, 1936, Serial No. 108,960

1 Claim. (Cl. 81—121)

An object of my invention is to provide a drain cock wrench of simple, durable and inexpensive construction.

A further object is to provide a wrench which is particularly adapted for operating drain valves which are difficult of access, such as those located on an automobile radiator.

A further object is to provide a wrench which has a wrench portion and a handle portion, the two being pivoted together and operable by pulling or pushing on the handle element to rotate the wrench element and thus open or close a drain valve as desired.

A further object is to provide a drain cock wrench which affords ready access to drain cocks located on the bottom of an automobile radiator where access thereto with a pair of pliers or the like is extremely difficult of accomplishment due to the proximity of the engine to the radiator.

With these and other objects in view, my invention consists in the construction, arrangement and combination of the various parts of the device, whereby the objects contemplated are attained, as hereinafter more fully set forth, pointed out in my claim, and illustrated in the accompanying drawing, in which:

Figure 1 is a perspective view of a drain cock wrench embodying my invention.

Figure 2 is a rear elevation of an automobile radiator showing two of the wrenches being used for manipulating drain cocks of the radiator.

Figure 3 is an enlarged sectional view on the line 3—3 of Figure 1 showing a friction washer connection.

Figure 4 is a side elevation showing the wrench adjusted to a position permitting operation of a slotted type of drain cock; and

Figure 5 is a similar view showing the wrench adjusted for opening an ordinary pet cock type of drain cock.

On the accompanying drawing I have used the reference numeral 10 to indicate an elongated handle member and A a wrench member. The handle member 10 is preferably provided with a loop 12 at one end thereof and with a flattened blade portion 14 at the other end thereof similar to a screw driver blade.

The wrench A comprises a body portion 16 formed of strap iron or the like having a portion 18 extending at right angles to the portion 16. The portions 16 and 18 are L-shape, with relation to each other.

Flanges 20 extend from the side edges of the portion 18 and these provide slots or jaws indicated at 22 and 24 respectively, arranged at one

side and the end of the wrench A. The end of the body portion 16 opposite the head formed by the flanges 20 and the portion 18 of the wrench is provided with a perforation 26.

The handle member 10 is provided adjacent the lower end thereof with a perforation 28, the blade 14 extending beyond this perforation. A pivot means such as a rivet 30 is extended through these perforations and a friction washer 32, such as a cupped washer of spring steel or the like, is interposed between the elements 10 and 16. The washer 32 serves the purpose of normally retaining the wrench A at any desired angle relative to the elongated handle 10.

Practical operation

In the operation of my device, a closed drain cock 34 of an automobile radiator 36 may be opened by adjusting the wrench A to an angle relative to the handle 10, as shown in the left half of Figure 2, and placing the slot 22 over the blade of the drain cock. Then by lifting on the handle 10, the wrench A will swing in the direction of the arrow a and result in opening the drain cock.

At the right side of Figure 2 an open drain cock 38 is illustrated, and by adjusting the handle as shown, placing the wrench on the blade of the drain cock and then pushing downwardly on the rod 10, the wrench A will swing in the direction of the arrow b which closes the drain cock.

These operations can be accomplished in a minimum of time without any difficulty whatsoever, the elongated character of the handle 10 permitting ready accessibility of the wrench portion of my device to the blade of the drain cock.

In Figure 4 a radiator 36' is illustrated having a drain cock 34' of the kind provided with a slot 40 for coaction with a tool therewith for opening the drain cock. With my tool, the wrench A 40 can be swung up to an out-of-the-way position as illustrated, and the blade 14 used in the slot 40 for opening the valve.

With the ordinary type of pet cock valve 34" as shown in Figure 5, the wrench A may be adjusted to an opposite position and the jaws 24 associated with the blade of the drain cock for operating it. The jaws 24, it will be noted, are slightly bowed outwardly at their centers to accommodate this type of drain cock.

Some changes may be made in the construction and arrangement of the parts of my device without departing from the real spirit and purpose of my invention, and it is my intention to cover by my claim, any modified forms of structure or

use of mechanical equivalents which may be reasonably included within their scope.

I claim as my invention:

- 5 In a drain cock wrench, a wrench member of relatively thick sheet metal and a separate elongated handle member, said wrench member comprising a shank having one end snugly fastened to one end of said handle member by a transverse pivotal connection permitting frictional rotation of said shank thereabout in a plane extending in the same direction as said handle member, and
- 10

having an integral wrench head at its other end comprising an arm extending substantially at right angles to said shank and a pair of spaced parallel flanges of substantially the same size and shape extending at right angles from opposite side edges of said arm in substantially the same direction as said shank but out of alignment therewith, said pivotal connection being sufficiently tight to prohibit free rotation of said shank thereabout.

10

EDWARD J. BROUHARD.
